(57) CLAIM

The ornamental design for an electric dental cleaner, as shown and described.

DESCRIPTION

FIG. 1 is a first perspective view of an electric dental cleaner showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion in FIG. 1; FIG. 10 is an enlarged view of the selected portion in FIG. 3;

FIG. 11 is an enlarged view of the selected portion in FIG. 5; and,

FIG. 12 is an enlarged view of the selected portion in FIG. 7.

The broken lines shown in the drawings depict portions of the electric dental cleaner that form no part of the claimed design.
